CORRECTIVE INSOLE

Hyman L. Whitman, East Bridgewater, Mass., assignor to The B. F. Goodrich Company, New York, N. Y., a corporation of New York

Application February 27, 1946, Serial No. 650,427

6 Claims. (Cl. 36—71)

1

This invention relates to devices for correcting human feet that tend to pronate or become flat, and especially to corrective insoles for that purpose.

It is an object of this invention to provide an insole construction which will correct human feet which through inherent structural weakness or because of abuse have rotated toward the inner border and have become flat.

A more specific object is to provide a corrective insole construction which will aid in achieving better foot balance and bone alignment in order to eliminate sources of foot discomfort and weariness experienced by those having pronated or flat feet.

Another specific object of the invention is to provide an insole construction which will aid in correcting certain inherent structural defects, namely, to correct shortness or hypermobility of the first metatarsal bone by raising the inside position of the heel sufficiently to shift a greater portion of the body weight outward and forward toward the fifth metatarsal bone, thus relieving undue stress upon the inner metatarsals.

The corrective insole of the present invention incorporates a supporting element placed in such position that it rotates the foot to the outside and at the same time raises the inside portion of the heel sufficiently to shift a greater portion of the body weight toward the fifth metatarsal, thereby effecting a more efficient weight distribution helpful in those cases of foot trouble caused either by shortness or hypermobility of the first metatarsal bone.

The invention will now be described with greater particularity with respect to specific embodiments illustrated in the accompanying drawings of which:

Fig. 1 is a plan view of an insole embodying the invention in a preferred form, portions of the insole being shown broken away to disclose the features of construction and the location of the supporting element.

Fig. 2 is a transverse sectional view taken along line 2—2 of Fig. 1.

Fig. 3 is a composite view consisting of a sectional view taken longitudinally of the insole along line 3—3 of Fig. 1, and showing in superposition, a dotted line representation of the bones of the foot during actual use of the insole.

Fig. 4 is a transverse sectional view taken vertically through the heel portion of a shoe of the soft athletic type in which the corrective insole of this invention has been installed and showing in particular detail the transverse disposition of the corrective insole with relation to other parts of the shoe.

Referring to the drawings: Fig. 1 shows an insole comprising a relatively thin top or cover layer 10, preferably of a smooth hard finished

2

material such as a coated square woven fabric, and a thicker bottom layer 11 of somewhat more resilient material such as the usual "rag stock" consisting of an inexpensive rubber composition containing a considerable amount of fibrous filler. The top layer 10 has a wing-like extension 12, extending, as shown in Fig. 1, from a point 13 somewhat rearwardly of the arch which would make it fall approximately under the tripod construction of the foot (formed by the intersection of the navicular, the talus and calcaneus bones of the foot) in the region back of the metatarsal bases to a point 13a well back on the heel, preferably near the end of the calcaneus or heel bone. The wing-like extension or flap 12 is designed to receive a portion of a supporting element and be adhesively secured thereto in order that the top surface of the insole and a projecting portion of the supporting element may be turned up to lie against the upper of the shoe.

A supporting element or lift desirably comprising two superimposed portions, is adhesively secured between the layers 10, 11 of the insole in a position immediately beneath the flap 12 and comprises, first, a relatively non-resilient lift portion 14 of high fiber "rag stock" or the like which has its longitudinal edges curved inwardly and which has its edges skived to feather edges entirely around the margins and preferably on the upper face so as to leave one face flat and on the other leave a crown or raised central portion 15 of considerable area as compared to the total area of the non-resilient portion. In a preferred embodiment, shown in Fig. 1, the lift element is shaped somewhat like a pointed ellipse with the longitudinal edges tapered to a common point at each end. The lift portion is preferably inserted between the layers of the insole to a depth at which a substantial portion of the normal curve of the inner border of the foot will fall across the crown of the supporting element. The feathered edges should preferably recede smoothly toward the outer border of the foot so as to eliminate any bumps or sharp unevenness in the surface of the insole and to permit the flap 12 to be laid against the side of the shoe without uncomfortable bumps or lumps. The flat under side of the non-resilient portion 14 is secured to the bottom layer 11 of the insole as by adhesives or stitching and a cushioning portion 16 of resilient material such as a layer of rubber sponge is secured over the crown 15 of the non-resilient portion 14, covering that portion of the crown contacted by the weight-supporting surfaces of the foot and preferably extending inwardly far enough to cover all the element 14 which lies within the boundaries of the normal insole. The cushioning layer 16 is a most important part of the supporting element in that it serves to eliminate the harshness of the non-resilient element.

For that reason care must be taken to see that the sponge cushioning position of the lift element is correctly placed over the lift element in order to smooth the harsh outlines of the crown and to effect a general cushioning action in the tripod region of the foot. The top layer 10 is secured adhesively to the bottom layer 11 throughout their contacting faces and both layers are adhered to the interposed supporting element in the zone occupied by it, the wing-like flap 12 being secured adhesively to the extending portion of the non-resilient lift portion 14 of the supporting element.

The insole of this invention may either be built into a shoe or it may be proportioned so that it may be inserted in a finished shoe as a supplementary insole. In either case the insole desirably is adhered to the shoe bottom to give a close and comfortable fit with the flap 12 extending a considerable distance upward along the upper 17 or side of the shoe and over the quarter lining 18 as shown in Fig. 4, the shoe also including the customary outsole 19, insole 20 and other usual or desirable elements of shoe constructions.

In Fig. 3 the bones of the foot have been indicated in dot and dash outline in their proper relationship to the insole as obtains during walking. The bones important to an understanding of the invention are the metatarsals M, the cuneiforms Cu, and the navicular N, talus T, and the calcaneus Ca. It will be seen that the thrust exerted by the lift portion of the supporting member will come in the instep region rearwardly of the metatarsal heads so as to be substantially below the tripod construction of the foot as indicated by the arrow at 21, in contrast to prior constructions in which the apex of the supporting member has been placed directly below the longitudinal arch, i. e. below the portion of the foot from the first metatarsal head back to the articulation of the navicular and the inner cuneiform.

Consideration of the nervous system of the human foot will reveal that the plantar or under surface of the foot is covered with a network of nerves, particularly the medial plantar nerve which extends across and between the metatarsal bones in close proximity thereto. It is easily seen, therefore, that if sharp localized pressure is applied, as is done in many of the so-called arch supports, behind or between the metatarsal heads, pressure will be exerted upon these nerves with concomitant painful symptoms. In addition the plantar surface of the foot is a complex maze of muscles which contract the toes and aid in the flexing of the foot while walking. Most of these muscles terminate in tendons at or near the metatarsal heads. Therefore it is easily seen how a thrust or pressure applied in the metatarsal zone during walking will irritate and bruise these muscles and tendons and provide a source of pain and irritation. The heel portions of the feet, however, are designed to carry as much as one-half the total weight of the body and are possessed of deep cushions of flesh and cartilage over the knob of the calcaneus to soften a thrust thereupon. Moreover, the heel section of the foot is not possessed of as many articulating muscles, tendons and nerves and is not as easily subjected to irritation as is the arch region and the region of the metatarsal heads.

With the main thrust of the supporting element in the corrective insole of this invention coming as it does under the tripod construction of the foot, the arch sections of the foot comprising the

metatarsals, the cuneiforms and the navicular are free to assume their natural arched positions and to be retained in that position merely by the natural state of tension or tonicity of the ligaments of the arch. Except in extreme cases of structural defects in the bones and ligaments of the arch no artificial support is necessary but it has been found that a large proportion of cases of foot trouble are due to faulty foot posture and weight distribution whereby the feet pronate and throw unusual burdens on the bones and ligaments of the arch until the strain manifests itself in areas of soreness and tenderness, particularly in the vicinity of the contiguous surfaces of the bones of the arch. Since the present corrective insole allows the bones of the arch to assume more nearly their natural positions these traumatic symptoms are alleviated or eliminated.

The insole of this invention may be made of leather or rubber and rubberized fabric, synthetic rubber and resin coated and impregnated fabrics and fibrous materials including the many forms of artificial leathery materials and others. For example, an insole for the soft athletic type shoe, such as tennis shoes, may comprise a substantial bottom layer of somewhat resilient rubbery material calendered upon a stout duck fabric backing and a top layer comprising a layer of finer gauge duck fabric coated with a smooth-finished layer of a perspiration-resistant material such as the plasticized polyvinyl chloride resins or the copolymers of vinyl chloride, vinyl acetate, vinylidene chloride, and others. In the stiffer leather shoes it may be more desirable to build the insole 35 of leather of appropriate kinds and thicknesses.

The supporting element incorporated in the insole of this invention may also be made of various kinds of leather, rubber and rubberized fabric, synthetic rubber and resin coated, and impregnated fabrics and fibrous materials, as well as the artificial leathery materials. For example, a supporting element suitable for incorporation into an insole for a soft athletic shoe or tennis shoe may have a relatively non-resilient lift portion made of fabric reinforced rubber of high carbon black loading or fabric-containing "rag stock" and preferably with two or more layers or lamina of fabric in order to furnish sufficient body and to prevent crumbling during the skiving operation. The cushioning portion is preferably made of sponge rubber but may be made of other similarly resilient materials such as sponge made from synthetic rubbers and resins and natural sponge, molded ground cork and the like.

Although especially valuable for use in soft-type shoes for which the corrective insole of this invention is especially well adapted, the invention also will be found useful in shoes of other types such as leather shoes, felt or canvas shoes, and the like.

Various modifications may be made without departing from the spirit and scope of the invention as it is defined by the following claims.

I claim:

1. An insole for supporting and cushioning the foot and for correcting feet that tend to pronate by raising the inner border of the foot so as to rotate the foot to the outer lateral border, said insole comprising a relatively thin top layer of smooth-finished material, a thicker bottom layer of resilient material, and a supporting element comprising a portion of a relatively rigid material and a cushioning portion of sponge rubber of substantially the same thickness as said relatively rigid material, said top layer of said insole having

a wing-like projection on the inner border thereof extending from a point on the insole which ordinarily would fall approximately beneath the intersection of the navicular, the talus and the calcaneus bones of the foot to a point well back on the heel of the foot, said relatively non-resilient portion of the supporting element having its edges skived on one face to a feather edge so as to leave a crown of considerable area as compared to the total area of the said portion, said supporting element having a portion of its flat side adhered to the said thicker bottom layer and having the said cushioning portion adhered overlying the crown of the non-resilient portion, the skived edges of the supporting element extending out to and being substantially coextensive with the wing-like portion of the insole so as to rest partly under the heel of the foot and partly over the contiguous portions of the shoe upper.

2. An insole for supporting and cushioning the foot and for correcting feet that tend to pronate by raising the inner border of the foot so as to rotate the foot to the outer lateral border, said insole comprising at least two layers, one a top layer of smooth-surfaced material and the other a bottom layer of relatively resilient material, said insole also comprising a built-in supporting element comprising a relatively rigid lift portion and a resilient portion of substantially the same thickness as said relatively rigid portion, said insole having a flap extending laterally from the top thereof from a point which normally would fall approximately under the point of intersection of the navicular, the talus and the calcaneus bones of the foot to a point well back on the heel, said flap carrying a portion of the supporting element, the combination when laid along the upper of the shoe tending to support the side of the foot to prevent rotation inwardly, said relatively rigid portion being shaped similarly to the flap of the insole and having its edges skived on one face to a feather edge to leave a crown of considerable area as compared to the total area of the supporting element, said supporting element being adhered crown face upwards within the said insole with one edge coextensive with said flap on the insole and another feathered edge inserted between the layers of the insole to a depth at which the normal curve of the inner border of the foot falls across the crown of the supporting element, and the resilient portion of the supporting element being inserted between the layers of the insole so as to overlie the crown of the supporting element beneath the weight-supporting surfaces of the foot.

3. In a corrective insole structure, an insole member generally of foot shape, a lift element comprising a relatively rigid portion and a relatively resilient cushioning portion of substantially the same thickness as said relatively rigid portion in superposed relation, said lift element being disposed in the shank region of the insole member but rearwardly of the arch of the foot and extending longitudinally of the insole member from the region normally approximately beneath the intersection of the navicular, the talus, and the calcaneus rearwardly to a position well underneath the calcaneus of the foot, the said element occupying a zone extending transversely from a region intermediate the normal margins of the insole to a region beyond the normal inner margins of the insole to provide a laterally extending flap, the arrangement being such as to provide a principal upward thrust in the region of the tripod construction of the foot.

4. In a corrective insole structure, a generally curved and tapered element of relatively rigid material disposed rearwardly of the arch of the foot and having its major axis extending from the region of the tripod rearwardly to a point well underneath the calcaneus, a portion of the curved element extending laterally beyond the normal inner margin of the insole to provide an extending flap-like portion, and a cushioning element of relatively resilient material of substantially the same thickness as said relatively rigid material overlying a portion of said curved element within the normal margins of the insole, the arrangement being such as to provide a principal upward thrust in the immediate region of the tripod construction of the foot.

5. An article of footwear having a corrective insole comprising a relatively thin top layer of smooth-finished material, a thicker bottom layer of resilient material, and a generally elliptical intermediate supporting member of relatively rigid material disposed between said layers extending rearwardly from a point normally approximately beneath the intersection of the navicular, the talus, and the calcaneus at least to a point beneath the lowermost portion of the calcaneus, said supporting member and said top layer extending laterally well beyond the normal inner edge of said insole to form a wing-like projection which is turned upwardly along the inner side of the foot, and a cushioning member of sponge rubber of substantially the same thickness as said relatively rigid material disposed between said supporting member and said top layer and extending over at least that portion of said supporting member which lies within the normal boundaries of said insole.

6. An article of footwear having a corrective insole structure comprising a generally foot-shaped insole member and a lift element, said lift element comprising a relatively rigid portion and a superposed relatively resilient cushioning portion of substantially the same thickness as said relatively rigid portion, said element being disposed in the instep region of said insole member rearwardly of the position normally beneath the base of the metatarsals and extending longitudinally of said insole member from the region normally approximately beneath the intersection of the navicular, the talus, and the calcaneus to a position well underneath the calcaneus, said element extending transversely from a region intermediate the normal margins of said insole member to a region beyond the normal inner margin of said insole to provide a projecting flap, said flap being turned upwardly along said normal inner margin.
